(57) **CLAIM**

The ornamental design for a sock with nonslip part, as shown and described.

DESCRIPTION

FIG. 1 is a top plan view illustrating an interior of a sock with nonslip part in a collapsed state in accordance with a first embodiment of our new design;

FIG. 2 is a left side elevational view thereof;

FIG. 3 is a right side elevational view thereof;

FIG. 4 is a front elevational view thereof, where a rear elevational view is identical;

FIG. 5 is a top plan view illustrating an exterior of the sock with nonslip part in the collapsed state in accordance with the first embodiment of our new design;

FIG. 6 is a bottom plan view thereof;

FIG. 7 is a cross sectional view along the line 7-7 in FIG. 5;

FIG. 8 is a front and left perspective view illustrating the sock with nonslip part in a three-dimensional, erected state in accordance with the first embodiment of our new design;

FIG. 9 is a top plan view illustrating an interior of a sock with nonslip part in a collapsed state in accordance with a second embodiment of our new design;

FIG. 10 is a left side elevational view thereof;

FIG. 11 is a right side elevational view thereof;

FIG. 12 is a front elevational view thereof, where a rear elevational view is identical;

FIG. 13 is a top plan view illustrating an exterior of the sock with nonslip part in the collapsed state in accordance with the second embodiment of our new design;

FIG. 14 is a bottom plan view thereof;

FIG. 15 is a cross sectional view along the line 15-15 in FIG. 13; and,

FIG. 16 is a front and left perspective view illustrating the sock with nonslip part in a three-dimensional, erected state in accordance with the second embodiment of our new design.
